United States Patent Office

Des. 183,951
Patented Nov. 18, 1958

183,951

CHENILLE TEXTILE FABRIC OR SIMILAR ARTICLE

William Stark, New York, N. Y., assignor to Aileen Mills
Company, Biscoe, N. C., a corporation of Delaware

Application September 10, 1957, Serial No. 47,682

Term of patent 14 years

(Cl. D92—1)

FIG. 1.

FIG. 2.

I claim:

The ornamental design for a chenille textile fabric or similar article, substantially as shown.
